UNITED STATES PATENT OFFICE.

KARL S. STRAND, OF NEW YORK, N. Y.

MATCH-BOX.

1,281,870.

Specification of Letters Patent. Patented Oct. 15, 1918.

Application filed February 10, 1917. Serial No. 147,813.

To all whom it may concern:

Be it known that I, KARL S. STRAND, a citizen of the United States, and a resident of New York, in the county of New York 5 and State of New York, have invented certain new and useful Improvements in Match-Boxes of that Type Known as a Single-Delivery Match-Box.

The object of this invention is to provide 10 a match-box having a lever which requires manual manipulation of a lever in order to secure a single match.

Another object is to provide a single delivery match box of an attractive form so 15 arranged that matches may be delivered therefrom one at a time, with ease, accuracy, and despatch.

With these and other objects in view, the present invention consists in the combination 20 and arrangement of parts as will be hereinafter more fully described and finally pointed out in the appended claims, it being further understood that changes in the specific structure shown and described may be 25 made within the scope of the claims, without departing from the spirit of the invention.

In the accompanying drawings forming a part of this specification, and in which like 30 numerals of reference indicate similar parts in the several views:—

Figure 1 shows a side elevational view partly in section of a match box embodying my invention.

Fig. 2 is a vertical sectional view.

Fig. 3 is a top view.

Fig. 4 is an interior view on line 4, 4 of Fig. 1.

In carrying out the aim of my invention, 40 I provide a single delivery match-box including a hopper which ends in a chute and from which extends a plurality of carrying arms which support the lowermost match as well as all of the matches within the chute, 45 with means for removing the arm to agitate the matches within the hopper and provide a positive release of the match to drop out of the chute upon a tray from which the match may be readily removed.

50 In carrying out the aim of my invention, I employ a base member to which an operating mechanism is secured, the operating mechanism being covered by means of a housing.

In the drawings, the numeral 1 represents 55 the bottom of the base, 5, the back, 7, the front and 6, 6, the two sides. As shown, the sides have the supporting ledges *a* while the front 7 is provided with the escape opening E. Held upon the ledges *a* is the base 60 plate 2, this base plate having the escape opening B, through which the matches, released from the hopper drop.

Secured to the base plate 2 in parallel spaced relation are the two side flanges 3, 3, 65 each having an edge 4 by means of which the sides are secured to the base plate 2.

The hopper as used in my invention comprises two similar side members C, and the back comprising the straight upper portion 70 8, the lower curved portion 9, and the chute forming wall 10, which ends in the securing flange 11. The front wall comprises the upper portion 12, the obliquely extending portion 13, and the chute forming wall 14, these 75 walls 10 and 14 extending parallel and forming a chute. The chute-forming wall 14 ends in the securing flange 15, the bolts *a'* being used to secure the flanges 11 and 15 to the base plate 2.

As shown in Fig. 2, the walls 10 and 14 have their inner faces extending in alignment with the opening B within the base plate 2.

Extending downward from the rear wall 85 8 is the inner rear wall 16 which has the curved bottom forming portion 17, and ends in the stub chute forming wall 18 forming a continuation of the wall 10. As disclosed, 90 the curved portion 17 of the inner wall 16 has the slot *b'*. The upper end of the inner wall 16 is flanged over the outer wall 8, as shown at *c'*.

Secured to the front wall 12 is the inner front wall 19 which is an obliquely held 95 stub wall and ends a suitable distance below the upper edge of the wall 12, this construction being clearly shown in Fig. 2, the upper edge *c'* of this wall 19 also being flanged over the upper edge of the outer wall 12. 100 Secured to the inner face of the inner front wall 19 is a spring push plate 20, this plate being of such a length that the same ends at a point slightly below the lower end of the curved inner wall portion 17.

The function of this spring is to shove the matches contained within the hopper upward upon the curved portion 17 to agitate

the same and thereby prevent clogging of the matches above the chute which is adapted to hold the matches in single layers in superposed position.

5 Located transversely near what forms the forward portion of the match box is the operating shaft D from which extends an operating handle 21. This shaft D is provided with an upstanding crank arm 22, and a 10 spring stop arm 23, this construction being best shown in Fig. 2.

The upward movement of the operating lever 21 is controlled by means of the stop pin F against which the stop arm 23 normally rests, this arm being forced against the pin by means of a spring, as will be more fully described hereinafter.

The depending stop arm 23 is in normal engagement with the upstanding push arm 25 secured to the rock shaft 24, this rock shaft 24 further being provided with the upstanding crank 26, which extends through a slot 4' within one of the flanges 3, as shown in Fig. 1. Secured to the projecting 20 end of this crank 26 is the slotted spring pressed connecting rod 27 which at its forward end is in engagement with the projecting end of the crank 26, while the rear end of this connecting rod 27 is in engagement 25 with the depending crank arm 28 forming a part of the crank shaft 29, this arrangement being shown in Fig. 4. The projecting end of the crank 26 limits the forward movement of the spring pressed 30 connecting rod 27, while the forward movement of the crank 26 is in turn, limited by means of the push arm 25, and being stopped by means of the stop arm 23. As shown, this shaft 29 is provided with a plurality of 35 curve ended carrying arms 30, these arms projecting through the slots d and e, located respectively within the walls 10 and 14, as will be understood in referring to Fig. 2.

The lowermost match as well as all of 40 the matches above within the chute are held by means of these curved carrying arms 30, three of these arms being shown in the drawings, as will be understood on referring to Fig. 4. Held within suitable ears 1' formed 45 upon the back 8 as shown in Fig. 2, is an arm shaft 31, this arm shaft having a crank 32 and being provided with a plurality of lifting arms 33, each lifting arm extending through a suitable opening within the rear 50 wall 8, as shown in Fig. 2, and being held below the curved bottom portion 17, each lifting arm 33, being adapted to move upward through a slot b' located within the curved bottom 17.

60 Extending from the lower end of the crank 32 forming a part of the shaft 31 is the slotted connecting rod 34, which has its forward end in engagement with the upstanding crank arm 22, the end of this arm 22 being held within the slot 3' formed

within the connecting rod 34 as shown in Fig. 2.

Held by means of the flanges 3, 3 is the rock shaft 35, this rock shaft having the striker arm 36 in normal engagement with the upstanding push arm 25, while extending downwardly and rearwardly from the shaft 35 is the rub plate 37 which is adapted to be held in spring pressed contact against the lower end of the plate 38, ending in the curved receiving arms 39, these arms being arranged to enter the chute through the slots e below the curved carrying arms 30. As disclosed in Fig. 2, the plate 38 is provided with a plurality of inwardly extending push arms 40 which pass through suitable openings within the lower portion of the wall 13. By means of these arms 40, the push plate 20 is forced inward to shove the matches contained within the 80 hopper upward upon the curved bottom 17.

In order to force the stop arm 23 against the pin F, I employ a coil spring 41 which has one end secured to the projecting end of the crank 22, while the other end 6' is hooked within an opening formed within the connecting rod 34. By means of this spring 41, the crank 22 is forced into engagement with the rear end of the slot 3' while the member 34 is retained in its retracted position, the result being that the arm 23 is stopped against the pin F. In order to normally force the lower ends of the carrying arms 30 into the chute and yieldingly hold the same therein, I provide 95 a coil spring K', as shown in Fig. 1, one arm 43 of which extends through an opening within the connecting rod 27, while the other arm 42 is held below the ear 8' extending from the side C of the chute as 100 shown in Fig. 1. This arm 43 normally forces the rod 27 forward into engagement with the end of the crank 26.

The slotted connecting rod 34 is similarly shoved outward so that its forward end is 110 in normal spring pressed engagement with the end of the crank arm 22 by means of a coil spring K which has one of its arms 46 extending through a slot within the rod 34 while the other arm 47 of this spring K is 115 held below an ear 45 as shown in dotted lines in Fig. 2.

Located below the chute opening B, is the chute plate 50 having the curved end 51, this plate 50 being held between the sides 120 52 and against the back 53.

The operating mechanism described is held within the housing A which is detachably secured to the base by means of the push ears 60 as shown in Fig. 4, which are adapted to extend through a suitable slot within the lower portion of the housing A. This housing A is merely used to cover the working elements and to prevent any one from reaching into the hopper and removing matches 130

therefrom. As shown in Fig. 2, this housing A is provided with an opening L through which the operating lever 21 extends.

The operation of my device is as follows:—

After the hopper is filled with matches, the lowermost match within the chute is held by means of the curved carrying arms 30. Now, in order to release a match, the operator 10 presses the lever 21 which results in the stop arm 23 shoving the upstanding push arm 25 inward. This inward movement of the arm 25 in turn results in the striker arm 36 being engaged to tilt the rock 15 shaft 35 resulting in the rub plate 37 shoving the curved receiving arms 39 inward through the slots e and into the path of the match, and below the same.

At u in Fig. 2, I have shown the inward 20 position of these receiving arms 39. At the same time that the receiving arms 39 enter the chute, the curved carrying arms 30 recede in that the rod 27 is actuated by means of the upstanding crank 26 to actuate the 25 crank 28 to rock the shaft 29 to swing the arm 30 out of the chute permitting the matches within the chute to drop upon the lower end of the receiving arms 39.

At the same time that these receiving arms 30 enter the chute, the push arms 40 also move inward, and being in engagement with the push plate 20, this plate is pushed inward so that all of the matches above the chute are forced upward upon the curved bottom 17 thus agitating the matches and preventing packing of the matches above the chute.

Simultaneous with this backward movement of the matches, there is imparted an upward movement to the matches within the 40 hopper, which is accomplished by means of the lifting arms 33 which, as the plate 20 enters the hopper, move upward from below through the slots b' to raise the matches so that the matches within the hopper above 45 the chute are simultaneously pushed backward and raised upward.

At v in Fig. 2 on dotted lines, I show the inward position of the plate 20, and at r on dotted lines, the upward position of the 50 arms 33. As shown, the limit of the excursion of the arms 30 is shown by means of the dotted lines u, while the maximum incursion of the arms 39 is shown by means of the dotted lines u. The extreme positions of the 55 arms 36 and 37 are shown by means of the dotted lines y and x, while the limit of the downward movement of the operating handle 21 is shown at o, the downward movement of the crank 22 being shown at p.

On the full downward stroke of the lever 60 21, the match is dropped from the arm 30 upon the arms 39. On releasing the lever 21, the receiving arms 39 pass outward liberating the lowermost match while simultaneously, the arms 30 enter inward and en-

gage the lowermost match held within the chute from escaping downward and as the members 39 recede the members 30 raise the matches within the chute upward so that as the lowermost match is released from the 70 arms 39, to drop through the opening B, the matches within the chute are held by means of the arms 30. As the members 39 recede the plate 20 as well as the lifting arms 33 also pass out of the hopper and assume their 75 normal positions. The inward movement of the member 23 is shown at n and the inward movement of the member 25 at m. As the match drops through the chute opening B and drops upon the plate 50, it is stopped 80 by means of the curved end 51 from which the same may be conveniently removed.

Having thus described my said invention, what I claim as new and desire to secure by U. S. Letters Patent is:—

1. A single delivery match box comprising a hopper ending in a chute, of a plurality of carrying arms held within said chute, a plurality of receiving arms held adjacent to said chute, a plurality of lifting arms 90 held below said hopper, an operating shaft, means for connecting said carrying arms to said operating shaft, means for connecting said receiving arms to said operating shaft, and means for connecting said lifting arms 95 to said operating shaft, whereby as said carrying arms are forced out of said chute said receiving arms are forced into said chute and said lifting arms are forced into said hopper.

2. In a single delivery match box, a hopper ending in a chute, a plurality of carrying arms within said chute, means for forcing said carrying arms out of said chute, a plurality of receiving arms held adjacent 105 to said chute, a push plate held within said hopper, means for connecting said push plate to said carrying arms, a plurality of lifting arms, and an operating means, whereby as said carrying arms pass out of 110 said chute said receiving arms enter said chute while said push plate moves inward and said lifting arms enter said hopper.

3. The combination in a match box of the character described including a hopper 115 and a depending chute, said chute having a plurality of slots, of a main operating shaft having a depending stop arm, of a rock shaft located below said operating shaft having an upstanding push arm in contact 120 with said depending stop arm, and an upstanding crank, a carrier shaft secured parallel to said operating shaft, said carrier shaft ending in a terminal crank, a plurality of curved carrying arms extending from 125 said carrier shaft through said slots, a connecting rod extending from said terminal crank and secured to said upstanding crank, a spring to force said connecting rod forward, whereby said push arm is normally 130

held in spring pressed contact with said depending arm, and a stop pin limiting the outward movement of said depending arm.

4. The combination in a match box including a hopper the bottom of which is provided with a plurality of slots and ending in a chute said chute having oppositely positioned slots, of a main operating shaft having an upstanding crank arm and a depending stop arm, of a rock shaft located below said operating shaft having an upstanding push arm and an upstanding crank, a carrier shaft, a plurality of carrying arms extending from said carrier shaft through the slots within said chute, said carrier shaft ending in a terminal crank, a connecting rod extending from said terminal crank, a spring to normally force said connecting rod forward, a stop pin limiting the forward movement of said stop arm, an arm shaft ending in a crank, a plurality of lifting arms extending from said arm shaft and arranged to pass through the slots within the bottom of said hopper, a connecting rod

extending from the crank of said arm shaft and secured to the crank arm of said operating shaft, a spring to normally force said last-mentioned connecting rod in one direction, a shaft, a striker arm extending from said shaft and in contact with said push arm, a rub plate extending from said shaft, a plate ending in a plurality of curved receiving arms said receiving arms being arranged to pass through the slots within said chute, said rub plate being in normal contact with said receiving arms, a spring push plate located within said hopper, and a plurality of push arms extending from said receiving arms and contacting with said plate whereby when said receiving arms are forced inward said push plate is also forced inward.

In testimony, whereof, I affix my signature in the presence of two witnesses.

KARL S. STRAND.
